CHALKBOARD VACUUM ERASER

Ha-Yung Lee, Flushing, N.Y.
(1235 Broadway, New York, N.Y. 10001)

Filed May 25, 1973, Ser. No. 364,103

Term of patent 14 years

Int. Cl. D19—06

U.S. Cl. D19—53

FIG. 1 is a front elevational view of a chalkboard vacuum eraser showing my new design, an intermediate portion of the hose being broken away for convenience of illustration;

FIG. 2 is a rear elevational view thereof;

FIG. 3 is a left side elevational view thereof;

FIG. 4 is a right side elevational view thereof;

FIG. 5 is a top plan view; and

FIG. 6 is a bottom plan view.

I claim:

The ornamental design for a chalkboard vacuum eraser, substantially as shown and described.
